UNITED STATES PATENT OFFICE.

JOHN JOHNSON, OF WORCESTER, MASSACHUSETTS.

DESIGN FOR A GEAR-WHEEL.

54,266.

Specification for Design.

Patented Dec. 9, 1919.

Application filed July 5, 1919. Serial No. 308,903. Term of patent 3½ years.

To all whom it may concern:

Be it known that I, JOHN JOHNSON, a citizen of the United States of America, residing at the city of Worcester, in the county of Worcester and State of Massachusetts, have invented a new, original, and ornamental Design for Gear-Wheels, of which the following is a specification, reference being had to the accompanying drawing, forming part thereof.

The figure is a plan view of a gear wheel showing my new design.

I claim:—

The ornamental design for a gear wheel, as shown.

JOHN JOHNSON.
